DISPLAY COVER STRUCTURE

Charles W. Boston, Kenmore, N. Y.

Application January 21, 1935, Serial No. 2,809

12 Claims. (Cl. 220—82)

This invention relates to display devices and it has particular relation to a front or cover display construction for presenting in an attractive manner perishable and semi-perishable articles, 5 such as bakery products and other comestibles.

One object of the invention is to provide a constant and uniform display of articles of merchandise quantities of which are being consumed from day to day and to provide replaceable merchandise displays according to the sale or disposition of the supplies of a given article.

Another object of the invention is to provide a demountable frame receptacle for receiving trays of merchandise and which is adapted to be applied to various types of conventional display covers and cabinet closures without materially altering their structure.

Another object of the invention is to provide an improved assembly of display cover and tray receptacle for use in conjunction with cartons of merchandise.

Another object of the invention is to provide an improved method of packaging and displaying articles of merchandise.

In displaying bakery products, especially biscuits and cookies, it has been found to be desirable both to the customer and to the wholesaler to supply the products in bulk form. There is a decided relationship between the sales of such bulk goods and the appearance of the display containers. In fact the goods can be sold much more rapidly from a freshly opened and full container or carton than from a carton which the customer notices is partially empty and in disarray. Efforts have been made to remedy the disadvantage of unattractive displays by the employment of types of display units which ostensibly appear to be full, although certain difficulties have been encountered in maintaining the proper appearance or maintaining the interest of the jobber to such an extent as to insure manipulation of the devices from time to time in order that they may be presented properly.

This invention is designed for the purpose of providing an improved arrangement wherein the cartons for display units always appear to be full and there is a definite rotation of fresh display articles according to the consumption of the articles from bulk containers. To this end a display tray is provided in each carton of articles and is removed at the time the new carton is opened and replaced in a display tray receptacle of the cover. After the cover has been closed the tray assumes substantially the same location 55 in the assembly as it had in the original carton.

This simple transfer of the tray from the original carton to the cover does not require detachment of any of the mechanical parts of the cover and does not materially inconvenience the jobber.

In the drawing—

Fig. 1 is a view partially in elevation and partially in fragmentary perspective of a container cover with a holder or receptacle incorporated therein and applied to a merchandise container;

Fig. 2 is a perspective of a holder or receptacle 10 constituting one of the principal features of the invention;

Fig. 3 is a fragmentary cross section, on a larger scale, taken substantially along the line III—III of Fig. 1;

Fig. 4 is a perspective similar to Fig. 2 and illustrating another form of receptacle;

Fig. 5 is a fragmentary cross section similar to Fig. 3 with reference to the application of the structure shown in Fig. 4;

Fig. 6 is a fragmentary cross section, on a larger scale, of a hinging portion of a cover including another form of connection in which the receptacle is hinged to the hinging element of the cover;

Fig. 7 is a fragmentary perspective of another form of assembly of receptacle in which the arms of the latter are saddled upon marginal portions of a glass window section of the cover closure;

Fig. 8 is a perspective of another form of closure for the cover in which the receptacle and the closure are formed of a single sheet of material;

Fig. 9 is a perspective of another form of closure and receptacle which also serve as a securing device for a window glass;

Fig. 10 is a fragmentary perspective of a display cabinet in which the invention is incorporated;

Fig. 11 is a diagrammatic vertical section of a display closure illustrating a preliminary step in inserting a tray or package of articles therein;

Fig. 12 is a diagrammatic section similar to Fig. 11 and illustrating the position of the tray after it has been inserted in the closure receptacle;

Fig. 13 is a diagrammatic section similar to Fig. 11 and illustrating the manner of removing a shielding portion of the tray after the latter has been installed for displaying a tray or package;

Fig. 14 is a fragmentary perspective of a carton of articles including a display tray or package; and

Fig. 15 is a perspective of a circular cover having the invention incorporated therein.

In practicing the invention a cabinet 20 (Fig. 10) is provided with horizontal shelves 22 that are adapted to support a series of cartons 23 containing supplies of articles of merchandise 25, such as cookies, biscuits, or like bakery products, which are customarily replenished in new cartons from time to time. After the carton 23 has been opened at one end, a removable frame 26 is normally applied about its open end in proper alignment with the shelves 22 and is provided with a rear frame section 27 (Fig. 1) embracing the open end of the carton 23. Rearwardly extending portions 28 of the frame section 27 are in the form of surrounding marginal flanges which 5 constitute the embracing portions of the cover about the end of the carton, and the front of the section 27 is formed with lateral flanges 29 terminating in beaded portions 30 which define the opening into the carton when the cover is open.

10 A display closure or door 32 of the frame 27 which serves also to close the open end of the carton 23, has a hinge connection 33 securing it to the rear frame section 27 and has rearwardly extending side flanges 35, as well as upper and lower flanges 36. One of the side flanges 35 has a beaded edge 39 which constitutes a part of the hinge connection 33. A window opening 40 surrounded by inwardly extending lateral flanges 43 is covered by means of a transparent window 15 glass section 45 resting against the rear sides of the flanges 43. One of the flanges 43 is sufficiently wide to accommodate a name plate or advertising surface 47. It will be observed that the flanges 43 are disposed at right angles to the flanges 35 and 36.

20 The glass 45 is removably mounted in the closure 32 by means of resilient wires 50 and 52, each of which has one of its ends pivoted upon a pin 53 that is mounted upon the flange 36 and 25 its other end is swingable inwardly and outwardly. Suitable beads or lugs 55 are struck inwardly from one of the side flanges 35 and the ends of the wire opposite their pivotal connections are sprung behind these beads. Intermediate beads or lugs 56 are struck inwardly from 30 opposite upper and lower flanges 36 and intermediate offset portions 57 of the resilient wires are snapped behind these beads to assist in maintaining the wires in place against the rear surface of the glass and to insure the proper position 35 of the glass in the closure.

35 A removable carton or tray holder 60, in the form of a frame receptacle composed of resilient sheet material, is provided with a back 62, forwardly extending resilient side arms 63 and also lower forwardly extending resilient tray seating arms 65. The forward end portions of the side arms 63 are provided with oppositely extending spacing webs 66 which are in turn provided with 40 rearwardly extending fingers 67 disposed substantially parallel to the forwardly extending portions of the arm. These fingers 67 are slidably inserted upwardly and underneath cooperating resilient fingers 68 (Fig. 3) which are struck 45 out from the intermediate opposite portions of the side flanges 35, thus preventing the receptacle from moving upwardly beyond the fingers 68.

The lower arms 65 are provided with angular 50 downwardly extending fingers 69, which rest upon the lower flange 36 and the glass securing wire 52 is disposed behind these fingers to prevent them from being accidentally withdrawn from the closure. The lower wire 52 is also disposed underneath the lower arms 65. These forwardly 55 extending arms 63 and 65 define the sides and

bottom of the receptacle and are offset inwardly of the closure flanges 35 and 36 in order that the receptacle may move through the opening defined by the beads 30 of the frame section 27 when the closure is in its closed position. The resiliency of the arms 63, which normally tend to spread, insures their firm engagement with the fingers 68.

60 The frame receptacle 60 can be removed from the closure by springing the lower wire 52 from engagement with the beads 55 and 56 and drawing the lower arms 65 rearwardly while moving the side arms 63 downwardly to disengage the fingers 67 and 68. Ordinarily it is not necessary to remove the receptacle 60 after it has been 10 installed, but in the event the window section is broken, or for other reasons, disassembly is desired, it can be accomplished without difficulty.

15 A display tray 70 is inserted into the frame receptacle 60 and it is held against displacement 20 by virtue of its upper edge being disposed beneath the overhanging upper flange 36 of the closure 32. Its lower edge rests upon the seating arms 65 of the receptacle. Thus the tray must be bent or slightly distorted rearwardly when removing 25 it from the closure.

25 In the form of structure shown in Fig. 4, a receptacle 75, which in general outline is similar to the receptacle 60, is formed of a section of resilient wire bent to form back sections 76, forwardly extending resilient side arms 77 and forwardly extending resilient lower arms 78. Oppositely extending lateral fingers 79 constitute the extremities of the arms 77, and each finger 79 in assembled relation to the closure (Fig. 5) is 30 snapped into a recess 80 formed by striking out a portion of the side flange 35. A downwardly offset bridge portion 82 connecting the lower arms 78 is adapted to be held in place by means of the lower wire 52, and in this connection, can be 35 snapped behind the struck out portion 56 of the closure flange. The display tray 70 can thus be held in the same relative position by the receptacle 75 and the closure 32 as in the structure described with reference to Fig. 1.

40 In the form of structure shown in Fig. 6, a receptacle 85, substantially the same shape as the receptacle 60, has its laterally extending side arm 86 offset by a web 87 at the side adjacent the hinge 33 of the cover 32, and an extension 88 45 parallel to the arm 86 is formed into a bearing barrel 89 through which the hinge pin 90 of the hinge 33 is disposed. In the position of parts shown in Fig. 6, the closure 32 is partially open as indicated by the relationship of the closure 50 flange 35 to the flange 28 of the frame 27. The receptacle arm 86 on the opposite side of the closure is provided with a finger 92 corresponding in relative position substantially to the web 87 and is normally snapped behind a bead or finger 55 93 that is struck out in such position in the side flange 35 that the finger 93 substantially contacts the window section 45 to assist in holding it in place. The remaining portions of the receptacle 60 can be provided with forwardly extending seating arms corresponding to the seating arms 65 of the receptacle 60. The receptacle thus normally 65 hinges with the closure 32, but can be hinged independently thereof about the same hinging axis when the finger 92 is released from the bead 93. 70

75 Referring to Fig. 7 a frame receptacle 95 includes forwardly extending arms 96 which are similar to the arm 63 and are formed with saddle like portions 97 which receive opposite edges of the window glass 45. It is apparent that the lower 75

arms can be formed in the same manner as those just described for receiving the lower edge of the glass 45, whereby the glass and the receptacle can be connected as a unit and inserted into the closure where it is held in place by the wires 50 and 52 in the manner specified with reference to the structure shown in Fig. 1.

Another form of closure 100 is shown in Fig. 8, which is adapted to be secured in the same manner as the closure 32 to the frame 27, and also has the same hinge connection 33 therewith as that previously described. A pair of strips 102, which can be stamped as integral parts of a sheet material of which the closure 100 is formed, are bent into proper form to constitute a frame-like receptacle for receiving the tray 70. A convenient method of forming a closure of this kind involves stamping of the strips in such manner that they are spaced slightly from opposite side flanges 103 of the closure. Each strip is bent downwardly, rearwardly and upwardly to form a trough or groove 105 in which the lower edge of the window glass 106 normally rests. Horizontal tray seating portions 107 extend rearwardly from the trough 105 and merge into angularly disposed back portions 108 formed by bending the strips upwardly. The strips are then bent at an angle to form folded portions 109, and from the folded portions, side arms 110 extend forwardly in offset relation to the flanges 103. Fingers 112 are bent laterally in opposite directions from the side arms 110 toward the flanges 103 and these fingers are normally snapped behind beads or fingers 113 struck out from the body of the flanges. The distance of the beads 113 to the front flange 115 of the closure is slightly greater than the thickness of the glass section 106, and the fingers 112 serve in cooperation with the trough 105, to maintain the glass in its proper position in the closure. Therefore, additional securing means, such as the wires 50 and 52 are not necessary in this form of closure. If desirable the side arms 110 can be sprung toward each other to release them and the receptacle sections 102 can be bent rearwardly in order to facilitate the insertion of the tray 70 therein, or the tray can be forced into the receptacle section 102 against the glass without releasing the fingers 112.

In the form of closure 120 shown in Fig. 9, a resilient frame 122 is provided to serve both as a receptacle for the tray 70 and as a securing means for maintaining the glass 123 in its proper place in the closure. This frame is formed with offset laterally extending heads 125 which are movable through openings 126 formed in adjacent upper extremities of side flanges 127 of the closure 120 and are prevented from being displaced from the openings by virtue of the reduced recesses 128 through which the heads 125 cannot be withdrawn. The heads 125 are normally urged upwardly into these recesses. From the heads 125, opposite side sections 129 of the frame 122, which is composed of resilient wire, extend downwardly to a location adjacent the medial portions of side flanges 127 where they are formed with lateral extensions 130 which are movable inwardly over struck out portions 132 behind which the extensions are normally snapped and anchored. The wire of the frame 122 extends rearwardly from the extensions 130 to provide sides 133 of a frame receptacle for holding the tray 70, and diagonal back sections 135 of the receptacle are bent from the rear ends of the extensions 133 toward the bottom of the closure, so as to intersect, as indicated at 136.

If desired, the back sections can be secured together at their intersection 136 by soldering or spot welding or they can merely contact each other.

Forward extensions 137 from the lower extremities of the back sections 135 are connected by an offset bridge portion 139 formed with fingers 140 which are normally snapped into recesses 142 formed in the lower flange 143 of the closure. The heads 125, extensions 130, and fingers 140 are normally urged by the resiliency of the frame 122 into their assembled and locked relation with the openings 126, struck out portions 132, and recesses 142, respectively, in order to hold the frame 122 firmly and in slightly tensioned or sprung relation in the closure.

In the assembled relation of the structural features described with reference to Fig. 9, the side sections 129 of the frame maintain the upper portion of the glass 123 in proper position and the bridge 139 and fingers 140 maintain the lower portion of the glass in proper position. However, the extensions 130 and fingers 140 can be sprung from the closure flanges and the frame 122 can be hinged outwardly about the axes of the heads 125 to provide for removal or replacement of the glass 123. The tray 70 can be inserted in or removed from the frame 122 without disturbing any of the connections of the frame to the closure flanges.

Referring to Fig. 14, it will be observed that the carton 23 containing the biscuits 25, or like articles, and which is designed for use in connection with the display frame 27, is assembled for shipment with the tray 70 preferably placed at the top of the carton in superposed relation upon the next lower layers 150 of the articles. In packing the carton 23 a suitable top 149 is provided to seal it. The tray can be provided with transverse intersecting partitions 152 and 153 of sheet material having a projecting flap 155 formed along one margin thereof. Suitable inwardly turned flanges 156 formed along three sides of the tray 170 overlap the marginal portions of the shield 153 and the end portions of the partitions 152, thus providing guides for the edges of the slidible shield 153.

The display tray 70 with the shield 153 is removed from the carton 23 and is inserted into the receptacle 60, or in any of the other like receptacles 75, 85, 95, 102, or 122, shown in the various figures of the drawings, and in the manner shown in Fig. 11 until the front of the tray which has the removable shield thereon registers with the opening 40. Thus the tray with the shield therein rests against the rear side of the glass 45. Then the flap 155 of the shield is in rearwardly bent position by virtue of its engagement by the upper rearwardly extending flange 36, as shown in Fig. 12, and in such position is accessible manually for withdrawal. Since the shield 153 is slidible in the tray, it can be withdrawn by pulling upwardly and slightly at an angle rearwardly upon the flap 155 in the direction indicated by the arrow in Fig. 13.

After the display tray 70 has been inserted so as to have its lower portion embraced snugly in the receptacle 60, the upper flange 36 of the closure 32 overhangs the upper edge of the tray 70 and prevents the latter from being accidentally displaced. The frame receptacle prevents the tray from being displaced in other directions. The flange 36 thus cooperates with the receptacle and with the closure glass 45 in maintaining the

tray in its proper position in the closure. Therefore, there is no danger of the articles 25 falling from the tray or being displaced therein incidentally to their installation into the position for display or after they have been finally positioned in the closure 32.

In fitting the frame 27 upon the end of the carton 23, after the display tray 70 has been removed therefrom and inserted in the closure receptacle, there is sufficient space in the carton to accommodate the receptacle 60 with its tray 70 in the space previously occupied by the tray in the carton. If the first or top layer were not in the form of a display tray suitable for removal and insertion into the receptacle, or if the cover with its closure receptacle were mounted upon the carton before the display tray were removed, the closure would not be movable to its closed position because it would be blocked by the tray. Hence, the space required for the top layer or display tray of articles is utilized in the packing of the original cartons and this space is also utilized when the tray is assembled into the receptacle because the latter fits into this space 25 when the display tray has been transferred and the cover assembled in closed relation with the carton. In this manner there is no waste of articles, space or structure.

In the form of the invention shown in Fig. 15, 30 a circular cover 170 is provided and which constitutes the top of a container of the type generally employed in displaying merchandise, such as pretzels. A glass window section 172 is mounted in the ordinary manner in this cover and a frame receptacle 173 is inserted in the cover. Resilient side arms 175 of the receptacle extend forwardly and are provided with fingers 176 which are secured upon a circular flange 177 provided upon the front wall of the cover 170. Lower 40 seating arms 178 extend from the lower portion of the frame receptacle and are provided with upwardly extending fingers 179 which are also secured upon the flange 177. A polygonal merchandise tray 180 can be packed in the same 45 manner as the merchandise tray 70 previously described, and is then inserted into the cover to rest between the arms 175 and upon the seating arms 178 in such manner as to display articles therein through the window section 172 while the tray 50 is thus held in proper place with respect to the frame receptacle 173 and the cover 170.

From the foregoing description it will be apparent that various types of cover frames are adapted to be incorporated with the frame tray receptacle without requiring a special form of cover frame, and that the display units including the structure disclosed will always appear to be full and neatly arranged. Likewise, provision is made for installation of display receptacle upon covers of the type already widely used at the present time, or the original equipment of display cover and receptacle can be manufactured from a single sheet of material or otherwise, in such manner as to perform the function of 55 maintaining both the merchandise tray and the glass window section in proper position in the closure.

It has been found that the use of a uniform and filled series of windows for articles of the 60 type described is so attractive that the sale of these articles is materially increased by the use of the invention described. Moreover, the arrangement of the display carton or tray is such that its contents may be sold when the articles 65 of an entire supply carton are exhausted. This

is contrary to former practice which has been to maintain the original display layer for so long a time that it is not suitable for sale when it is finally removed.

Although several forms of the invention have 5 been shown and described in detail, it will be apparent to those skilled in the art that the invention is not so limited but that various changes may be made therein without departing from the spirit of the invention or from the scope of the 10 appended claims.

I claim:

1. A display unit for displaying trays of merchandise comprising an upright frame section adapted to be mounted upon an open end of a 15 merchandise container, a windowed display closure opening outwardly and forwardly from the frame section, and a frame like receptacle disposed in cooperation with the closure to form a tray receiving structure, said receptacle having a 20 tray receiving structure, said receptacle having opposite forwardly extending sides and also having a forwardly extending tray seating lower portion, said sides and upright side portions of the closure having releasable interlocking means normally holding the receptacle against either upward or rearward movement with respect to the upright frame sides, the tray seating lower portion of the closure being supported upon the lower portion of the closure.

2. A display unit for displaying trays of merchandise comprising an upright frame section adapted to be mounted upon an open end of a merchandise container, a windowed display closure having rearwardly extending flanges and opening outwardly and forwardly from the frame 35 section, a transparent window section mounted in the closure, a frame like receptacle disposed in cooperation with the closure to form a tray receiving structure for displaying articles against the rear of the window section, said receptacle having opposite forwardly extending sides and including angularly turned sections normally bearing against the rear side of the window section, said upright sides and upright sides of the closure having releasable interlocking fingers 45 normally holding the receptacle against either upward or rearward movement with respect to the upright frame section, said receptacle having a forwardly extending tray seating lower portion, a portion of the tray seating lower portion normally bearing against the rear surface of the window section and being formed with means releasably interlocking with a portion of the lower side of the closure whereby the receptacle serves both as a window section securing means and 50 as a holder for a tray of merchandise.

3. A display unit for displaying trays of merchandise comprising an upright frame section adapted to be mounted upon an open end of a merchandise container, a windowed display closure opening outwardly and forwardly from the frame section, and a frame like receptacle disposed in cooperation with the closure to form a tray receiving structure, said receptacle having opposite forwardly extending sides and also having a forwardly extending tray seating lower portion, upright side portions of the closure having projecting struck out portions, the side portions of the receptacle fitting underneath and about said struck out portions to maintain the 60 receptacle against either upward or rearward movement, the lower portion of the closure having means for supporting the tray seating lower portion of the receptacle.

4. A display unit for displaying trays of mer- 75

- chandise comprising a frame section adapted to be mounted upon an open end of a merchandise container, a windowed display closure opening outwardly from the frame section and having a hinge connection securing it to the frame section, a frame like receptacle disposed in cooperation with the closure to form a tray receiving structure, said receptacle having opposite forwardly extending sides and also having a forwardly extending tray seating lower portion, one of the receptacle sides having a hinge connection coaxial with and forming a part of the first mentioned hinge connection, whereby the receptacle is pivotal concurrently with or independently of the closure about the hinge connection axis, and means for releasably locking the other side of the receptacle to an adjacent side of the closure.
5. A display unit for displaying trays of merchandise comprising a frame section adapted to be mounted upon an open end of a merchandise container, a windowed display closure opening outwardly from the frame section, a frame like receptacle composed of a resilient wire, said receptacle having opposite forwardly extending wire sides formed with lateral fingers, said receptacle having forwardly extending tray seating lower wire portions formed with downwardly extending fingers, and locking means formed upon the closure to cooperate with the fingers of the wire sides and seating portions, said receptacle being springable into and out of engagement with the locking means to maintain the receptacle and closure in proper relation to receive a tray of merchandise.
6. A display unit for displaying trays of merchandise comprising a frame section adapted to be mounted upon an open end of a merchandise container, a windowed display closure opening outwardly from the frame section, a transparent window section mounted in the closure, a frame like receptacle composed of resilient wire, said receptacle having opposite forwardly extending wire sides formed with lateral fingers, said receptacle having forwardly extending tray seating lower wire portions formed with downwardly extending fingers, locking means formed on the closure adjacent edges of the window section and engaging the fingers of the wire sides and seating portions, said receptacle being springable into and out of interlocking engagement with the locking means to maintain the receptacle and closure in proper relation to receive a tray of merchandise, said window section being disposed between said fingers and portions of the closure to hold said section against displacement.
7. A display unit for displaying trays of merchandise comprising a frame section adapted to be mounted upon an open end of a merchandise container, a windowed display closure opening outwardly from the frame section, a transparent window section mounted in the closure, a frame like receptacle composed of resilient wire, upper end portions of the wire being anchored to opposite upper portions of the closure, portions of the resilient wire adjacent its upper end portions overlapping edge portions of the window section, intermediate portions of the wire having lateral fingers, locking means formed on intermediate portions of the closure and normally engaging the fingers, said wire extending rearwardly and downwardly to form sides and back of a tray receiving receptacle to display merchandise, and lower tray seating portions of wire extending forwardly from the back and formed with down-
- wardly disposed lower fingers, the lower portion of the closure being formed with means normally interlocking with said lower fingers, said window section being disposed between a portion of the closure and portions of the resilient wire to maintain the window section in the closure, said resilient wire being springable to release the several fingers from the interlocking portions of the closure.
8. A display unit for displaying trays of merchandise comprising a frame section adapted to be mounted upon an open end of a merchandise container, a windowed display closure opening outwardly from the frame section, a transparent window section removably mounted in the closure, a frame like receptacle composed of resilient wire, upper end portions of the wire being detachably pivoted to opposite upper portions of the closure, portions of the resilient wire adjacent its upper end portions overlapping marginal portions of the window section, intermediate portions of the wire having lateral fingers, locking means formed on intermediate portions of the closure and normally engaging the fingers, said wire extending rearwardly and downwardly to form sides and back of a tray receiving receptacle to display merchandise, and lower tray seating portions of wire extending forwardly from the back and formed with downwardly extending fingers, the lower portion of the closure being formed with means normally interlocking with said downwardly disposed fingers, said window section being disposed between a portion of the closure and portions of the resilient wire to maintain the window section in the closure, said resilient wire being springable to release the several fingers from engagement with the interlocking portions of the closure and being swingable rearwardly about its upper pivotal connections to provide for removal of the window section.
9. A display unit for displaying trays of merchandise comprising a frame section adapted to be mounted upon an open end of a merchandise container, a windowed display closure opening outwardly from the frame section, a transparent window section disposed in the closure, a marginal portion of said closure having an integral extension bent to form a seat, one edge of the window section being held against forward and rearward movement in said seat, said integral extension having side, back and tray seating portions to form a tray receiving receptacle, and means for connecting the extension to the body of the closure at a location remote from the seat for the window section.
10. A display unit for displaying trays of merchandise comprising a frame section adapted to be mounted upon an open end of a merchandise container, a windowed display closure opening outwardly from the frame section, a transparent window section disposed in the closure, a marginal portion of said closure having an integral extension to form a trough like seat, one edge of the window section being held against forward and rearward movement in said seat, said extension having side, back and tray seating portions forming a tray receiving receptacle, a portion of the extension remote from the trough like seat contacting the window section to maintain the latter in place in the closure, means provided on the closure and cooperating with the last mentioned portion of the extension to maintain the latter normally locked against the window section.
11. A display unit for displaying merchandise

comprising a frame section adapted to be mounted upon an open end of a merchandise container, a windowed display closure opening outwardly from the frame section, a glass window section removably mounted in the closure, a frame of 5 resilient wire, upper opposite end portions of the wire having laterally extending heads, upper opposite portions of the closure having openings including reduced recesses for detachably and pivotally locking the heads, said heads normally being urged upwardly into the reduced recesses by the resiliency of the wire, portions of the resilient wire adjacent its upper ends overlapping marginal portions of the window section, intermediate 10 portions of the wire having lateral fingers, locking means formed on intermediate portions of the closure and normally engaging the fingers, said wire extending rearwardly and downwardly to form sides and back of a tray receiving receptacle, and tray seating lower portions of wire extending 15 forwardly from the back and formed with lower fingers, the lower portion of the closure being formed with means normally interlocking with said lower fingers, said window section being

disposed between a portion of the closure and portions of the resilient wire to maintain the window section in the closure, said resilient wire being springable to release the several fingers from engagement with the interlocking portions of the 5 closure.

12. A display device comprising a frame section adapted to be mounted upon the open end of a merchandise container, a display closure movably mounted upon the frame section, a removable 10 transparent window section carried by the closure, a resilient structure composed of continuous elongate sections providing a combined fastener and display tray receptacle mounted upon the closure, said structure and closure having a plurality of cooperating means for holding the window section in place in the closure, and said structure having portions extending from certain of the means and defining the form of the tray receptacle for removably receiving a tray of merchandise articles when the structure is in operable relation to hold the window section in the closure. 15 20

CHARLES W. BOSTON.
